(57) **CLAIM**

The ornamental design for an adhesive cleaner, as shown and described.

DESCRIPTION

FIG. 1 is an upper front perspective view of an adhesive cleaner, showing our new design;

FIG. 2 is a front elevation view thereof, the rear elevation view being a mirror image thereof;

FIG. 3 is a top view thereof;

FIG. 4 is a bottom view thereof;

FIG. 5 is a right side elevation view thereof;

FIG. 6 is a left side elevation view thereof;

FIG. 7 is an upper front perspective view thereof in its intended environment; and,

FIG. 8 is another upper front perspective view thereof in its intended environment.

The portions of the adhesive cleaner shown in broken lines form no part of the claimed design.

The broken line showings of FIGS. 7 and 8 of a case and a handle are for the purpose of illustrating environmental structure and form no part of the claimed design.
